UNITED STATES PATENT OFFICE.

TOLIVER LYNN CHISHOLM, OF ATOKA, INDIAN TERRITORY, ASSIGNOR OF ONE-THIRD TO ROBERT M. GRUBBS, OF SAME PLACE.

DESIGN FOR A STRAP-HINGE.

SPECIFICATION forming part of Design No. 26,381, dated December 8, 1896.

Application filed October 21, 1896. Serial No. 609,617. Term of patent 7 years.

To all whom it may concern:

Be it known that I, TOLIVER LYNN CHISHOLM, a citizen of the United States, residing at Atoka, in the Choctaw Nation and Indian Territory, have invented and produced 5 a certain new and original Design for Strap-Hinges; and I do declare the following to be a full, clear, and exact description of the invention, such as will enable others skilled in 15 the art to which it appertains to make and use the same.

My invention relates to a design for a strap-hinge. It relates to the entire configuration of the hinge, and especially to a hinge formed 15 of sheet metal.

My invention relates particularly to a hinge as illustrated in the accompanying drawings, in which—

Figure 1 is a perspective view of a hinge 20 embodying my design. Fig. 2 is a front elevation of the same. Fig. 3 is a top plan view, and Fig. 4 is a longitudinal central section of the same.

The leading features of my design appear 25 in the following description.

The upper and lower edges 11' of the plates

5 and 8 are straight and parallel with each other, and they each extend outwardly in curved lines 2 2 and 2' 2', converging to the semicircular ends 3 3, and the face of the 30 hinge is provided with the usual countersunk screw-orifices 4 4.

The inner vertical edge of the plate 5 is bent around on itself to form a vertical sleeve 6, from which a short rectangular arm 35 7 extends at a right angle to said plate 5.

The contiguous vertical edge of the plate 8 is bent around on itself at the top and bottom to form two vertical sleeves 9 9, and from each of these a short rectangular arm 40 10 extends at a right angle to the plate 8.

Having thus fully described my invention, what I claim as new, and desire to secure by Letters Patent of the United States, is—

The design for a hinge, substantially as 45 herein shown and described.

In testimony whereof I hereunto affix my signature in presence of two witnesses.

TOLIVER LYNN CHISHOLM.
